UNITED STATES PATENT OFFICE.

WILLIAM J. HARRIS, JR., OF NEW YORK, N. Y., ASSIGNOR TO THE SURFACE COMBUSTION COMPANY, INCORPORATED, OF TOLEDO, OHIO, A CORPORATION OF NEW YORK.

FIRING ARRANGEMENT FOR MUFFLE FURNACES.

Application filed September 26, 1927. Serial No. 221,914.

This invention relates to improvements in firing arrangement for furnaces having two parallel heating chambers in order that two parallel lines of articles to be heat treated 5 may be passed through the furnace in opposite directions. It is an object of the invention to provide a firing arrangement for furnaces of the type indicated such as will enable the heating 10 chambers to be in the form of muffles, and which will enable gas burners to be employed for heating purposes. Practical considerations limit the use of burners to one side only of each muffle and as a consequence 15 the tendency has been for one side of the muffle to become more highly heated than the other. My firing arrangement overcomes this objection and enables uniform heating on all sides of the muffle to be obtained. 20 In accordance with the present invention, a series of gas burners are positioned to fire through the outside walls of the furnace into combustion chambers below the individual muffles, and means are provided for equalizing 25 the amount of hot gases which flow upwardly along the muffle side walls. Said means preferably takes the form of a perforated partition arranged in the combustion chamber and towards which the burning fuel is directed. The burning gases on 30 reaching the partition wall will in part pass through the partition and flow upwardly along the far side of the muffle, the balance of the gases flowing back toward the burner and upwardly along the near side of the 35 muffle.

For a further understanding of the invention, reference is made to the detailed description taken in connection with the accompanying drawings forming part of this 40 specification,

Referring to the drawing, Fig. 1 is a vertical transverse section through the furnace, showing my invention applied thereto. Fig. 45 2 is a horizontal transverse section taken on line 2—2 of Fig. 1. Fig. 3 is a plan view showing more or less diagrammatically the type of furnace in connection with which the present invention has been designed for use.

50 In the drawing, 10 and 12 indicate, respectively, two heating chambers of the muffle type, these chambers extending in parallel relation throughout the length of the furnace, generally indicated at 14 in Fig. 3.

The adjacent sides of the muffles are separated from each other by a division or party wall 16 forming part of the furnace construction.

Gaseous fuel is introduced through the side walls 24 and 26, respectively, of the 60 furnace by means of burners generally indicated at 28 and 30 suitably positioned in the furnace side walls. These burners are so positioned that the burning fuel is entered into the combustion chambers below the bottom of the muffles and consequently tends to flow toward the division wall 16 between the muffles. In order to divert some of the burning gases upwardly into the space between the wall in which the burners are positioned 65 and the adjacent side wall of the muffle, there is provided between the bottom of the muffle and the floor of the combustion chamber, a baffle or partition 32 having perforations 34 therein through which the burning 70 gases may pass. The partition extends longitudinally of the muffle chambers and is positioned at the far side of the muffle. It will be readily appreciated that the burning 75 gases flowing from the burners will in part pass through the openings or perforations 34 in the partition 32 and flow upwardly into the space between the division wall 16 and the adjacent side of the muffles. The 80 balance of the gases will flow back towards the burners and up into the space alongside the outer or opposite wall of the muffles. By this relatively simple arrangement, burning 85 gases from the burners are caused to flow uniformly up along sides of the muffle 90 with the result that the muffle is uniformly heated throughout.

Each burner preferably fires into an individual combustion space formed between parallel walls 36 positioned transversely of 95 the muffle chambers as clearly indicated in Fig. 2. A series of upright spaced baffles 37 are provided in the muffle side wall spaces, the spaces between the baffles forming passages up which the hot gases from the combustion chamber must flow before they may 100 flow longitudinally of the muffles toward the exit flue not shown. By this means the heating gases from the burners are confined to localized areas of the muffles and thus enabling better control of the heating operation 105 to be obtained.

As previously indicated, the work will be

carried through the heating chambers in a continuous manner. In Fig. 3, the conveying mechanism is generally indicated at 44 and, as shown, consists of an endless conveyer the two runs of which are arranged in a horizontal plane, one run being associated with one heating chamber and the other run with the other heating chamber. The material to be heated is placed on the conveyer at 10 each end thereof. As shown in Fig. 3, there is a loading point at "A" to the left and a loading point at "B" to the right. Opposite these points at the same end, is a corresponding unloading point.

15 The operation of the furnace is continuous and the conveyer is moving constantly. The conveying system forms no part of the present invention, the system being substantially the same as that disclosed in Patent 20 #1,603,014. It may be stated that the two runs of the conveyer are confined to suitable tracks generally indicated at 46 in Fig. 1, and depending through slots in the roof of the furnace are suitable carrier elements 48 25 from which the work to be treated is suspended in any suitable manner.

What is claimed is:

1. The combination with a furnace chamber having a muffle therein the sides and 30 bottom of which are disposed in spaced relation with respect to the sides and bottom of said chamber, of means for heating the muffle comprising fuel-burning means adapted to direct the burning fuel from one side 35 of said chamber toward the opposite side thereof below the bottom of the muffle whereby the burning fuel tends to enter the space between the muffle and chamber side wall most remote from said fuel-burning 40 means, and means interposed in the normal path of flow of the burning fuel for restricting the area of entry of the burning fuel into said space.

2. The combination with a furnace chamber having a muffle therein the sides and bottom of which are disposed in spaced relation with respect to the sides and bottom of said chamber, of means for heating the muffle comprising fuel-burning means adapted to 45 direct the burning fuel from one side of said chamber toward the opposite side thereof below the bottom of the muffle whereby the burning fuel tends to enter the space between the muffle and chamber side wall most 50 remote from said fuel-burning means, and a perforated baffle interposed in the normal path of flow of the burning fuel for restricting the area of entry of the burning fuel into said space.

60 3. The combination with a pair of furnace chambers arranged side by side with a vertical division wall between them and each chamber having a muffle therein the sides and bottom of which are disposed in 65 spaced relation with respect to the sides and

bottom of their respective chambers, of means for heating the muffles comprising for each chamber fuel-burning means adapted to direct the burning fuel from points along the outside walls of the furnace toward that 70 portion of the division wall extending below the bottom of said muffles whereby the burning fuel tends to enter the space between said wall and the adjacent side of the muffle, and means interposed in the normal 75 path of flow of the burning fuel for restricting the area of entry of the burning fuel into said spaces.

4. The combination with a pair of furnace chambers arranged side by side with a vertical division wall between them and each chamber having a muffle therein the sides and bottom of which are disposed in spaced relation with respect to the sides and bottom of their respective chambers, of means 80 for heating the muffles comprising for each chamber fuel-burning means adapted to direct the burning fuel from points along the outside walls of the furnace toward that portion of the division wall extending below 85 the bottom of said muffles whereby the burning fuel tends to enter the space between said wall and the adjacent side of the muffle, and a perforated baffle interposed in the normal path of flow of the burning fuel for 90 restricting the area of entry of the burning fuel into said spaces.

5. The combination with a furnace chamber having a muffle therein the sides and bottom of which are disposed in spaced relation with respect to the sides and bottom of said chamber, of transversely extending partitions dividing the space between the bottom of the muffle and chamber into channels, 100 fuel-burning means firing into said channels 105 from one end thereof, and means extending across said channels adjacent the other end thereof for limiting the amount of burning fuel that may pass into the space between the adjacent muffle side wall and chamber wall. 110

6. In combination a furnace chamber, a muffle within the chamber, means for introducing heating gases below the muffle in a direction transverse to the length thereof and means for diverting a portion of the 115 heating gases back to the side wall nearest said means.

7. In combination, a longitudinally extending furnace chamber having a muffle therein, a series of upright baffles between the side walls of the muffle and furnace chamber, a preferred baffle extending longitudinally of said chamber below the muffle and positioned nearer one side wall of the chamber than the other, and a series of 120 burners firing through that furnace side wall most remote from said perforated baffle.

In testimony whereof I affix my signature.
WILLIAM J. HARRIS, JR.
